INTERLOCKING CONNECTER FOR
DENTAL USE

Armand M. Oppenheimer, New York, N. Y.

Application August 1, 1932, Serial No. 627,193

2 Claims. (Cl. 32—6)

My invention relates to certain new and useful improvements in an interlocking connector or attachment for non-removable dental bridge-work or the like, as herein fully described and as shown in the accompanying drawing.

5 Heretofore, one of the outstanding disadvantages inherent in non-removable dental bridge-work or the like, has been the uncleanliness of the inaccessible parts with consequent detrimental effects upon local and general health.

10 The objects of my invention are:

First, to provide an interlocking connector with which one or more pontics, or the like, may be connected with each other or with one or more piers or abutments, so as to allow the passage 15 of dental floss or similar agent to be designated herein as "a flexible cleaning agent", through and between the members of said interlocking connector or connectors, and thence under the pontic or pontics, or the like, cleaning the inaccessible portions of the appliance and abutments; or with which two or more teeth may be locked together and remain similarly cleanable.

Second, to combine with the above mentioned 20 improvement an efficient locking device which will allow the passage of said flexible cleaning agent, while absolutely preventing any independent movement of the abutments or pontics, or the like, except as hereinafter described.

Third, to combine with the aforementioned 25 features the added advantage of a limited scope of movement between the cooperating parts of the connector, thus permitting the degree of independence in movement of the abutment teeth necessary for normal function and health.

30 Further objects are to provide an interlocking connector as herein described, which can be easily and inexpensively manufactured, and which can be incorporated in dental bridgework by those skilled to accomplish the same; and such other advantages as may be implied and evident in these specifications and drawing:—

Figure 1 is a view in elevation of the male member. Figure 2 is a side view of the male member. Figure 3 is a sectional view of the male member taken through the line 3—3, on Figure 2. Figure 4 is a view in elevation of the female member. Figure 5 is a sectional view of the female member, through the line 5—5, on Figure 4. Figure 6 is a sectional view of the female member, taken through the line 6—6 on Figure 4. Figure 7 is a view of a selected application of the interlocking connector as incorporated in a dental bridge, showing the course of dental floss or similar flexible cleaning agent as it is passed through

and between the members of the connector, and thence under the pontic to the other bridge abutment. Figure 8 is a sectional view of the interlocking members as assembled and shown in Figure 7.

5 The male member 23, Figures 1, 2 and 3, is comprised of a plate 1, provided with a hooklike extension 2.

The female member 24, Figures 4, 5 and 6, is comprised of a plate 9, presenting a groove 10, adapted to receive the hooklike extension 2 of the male member, and a spur 11, adapted to be received into the notch 1 of the male member. Said groove 10, terminates in a pocket, the floor of which is marked 14, and from said pocket two channels, 12 and 13, one on each side, run laterally and curve downward and outward to emerge on the face of the plate on either side of the spur 11. The purpose of these channels 12 and 13, as will be seen more clearly below, is to permit dental floss or similar flexible cleaning agent to be drawn down along the floor 14, of the pocket of the female member and thence upward and over the spur 11, of said member when the male and female members are locked in position.

25 In Figure 7, is seen one application of the interlocking connector in a selected dental bridge. The lower first molar is missing. The lower second bicuspid 15, and the lower second molar 17, serve as abutments. The lower first molar space 30 is occupied by a pontic composed of a porcelain facing and tip 16, and a metallic backing 19. Said metallic backing 19, is in this case, soldered directly to an inlay 18, cast to be seated in a specially prepared cavity in the abutment 15. The 35 pontic is connected to the lower second molar abutment 17, by means of the interlocking connectors herein described. For that purpose an inlay 20, has been cast to fit a specially prepared cavity in the abutment 17, and into this inlay 40 has been soldered the female member 24, of the interlocking connector in the position shown. Into the metallic backing 19, of the pontic, has likewise been soldered the male member 23, of the interlocking connector. Dental floss 21, is shown 45 in successive positions passing through and between the members of the connectors, and underneath the pontics. Position 21—A shows dental floss about to enter between the members. Position 21—B shows the dental floss half way down 50 along the hooklike extension 2 of the male member 23. Position 21—D shows the floss emerging from the cervical region of the passage between the two members, and into the interproximal space, between the pontic and the abutment 17. 55

Positions 21—E and 21—F, show the dental floss passing underneath the pontics and position 21—G shows it in the interproximal space between the pontic and abutment 15.

- 5 In Figure 8, the male member 23 is shown soldered to the metallic portion 19 of the pontic, and the female member 24 soldered into the inlay, all as shown in Figure 7. The space 22, between the spur 11, of the female member 24 10 and the hook 2 of the male member 23 is devised to allow the male and female members to be wedged apart by the dental floss or similar agent, passing between them as shown in Figure 7, and also to permit the degree of independence of 15 movement of the abutments necessary for normal function and health.

The male and female members 23 and 24, are to be manufactured of any suitable and stiff material such as platinized gold.

- 20 Ordinarily the female member 24 is intended to be attached to an abutment tooth by means of an inlay or other suitable means of attachment, substantially as shown in Figure 7. The methods by which this may be accomplished are 25 well known and in common use. Likewise, the male member is to be inseparably joined to the metallic portion of the pontic, in such position that it will accurately lock with the female member when the bridge is assembled. This too may 30 be accomplished by well known methods in common use. Of course, the male and female members might conceivably be reversed in their position in the bridge, the male member being attached to the abutment and the female member 35 to the pontic. Or the interlocking connector might be placed interposed between two pontics. Furthermore, two or more connectors might be used in the same appliance. Another application of this principle of interlocking connection 40 is seen in the splinting of two or more neighboring teeth to each other, by means of the herein described connectors. Other uses of the connectors may present themselves in many applications besides the aforementioned.

In all cases dental floss or similar flexible cleaning agent may be passed between the members of the connector, and a definite locking in all directions obtained, together with all the other advantages herein described.

Thus, realizing that considerable variation is possible in details of construction and application, I do not intend to limit myself thereto, except as pointed out in the following claims, in which it is my intention to claim all the novelty 10 inherent in the device.

I claim:

1. An interlocking connector for dental use consisting of two members, a male member provided with an inclined finger; and a female member provided with a pocket to receive said inclined finger of said male member, and two channels extending from the base of said pocket of said female member laterally and to the face of said female member; said male and female members 20 interengaging in such a manner as to prevent separation when incorporated into a dental appliance permanently fixed in the mouth, sufficient clearance being provided between the coapt⁵ing parts of said male and female members to permit the forced passage of dental floss entirely thru and between the opposing surfaces of said male and female members when locked.

2. A flossable interlocking connector as herein described, consisting of two members, a male member provided with an inclined finger, and a female member provided with a pocket to receive said inclined finger of said male member and two lateral channels extending from the base of said pocket of said female member to the face of said female member, sufficient clearance being provided between the coapt³⁵ing parts of said male and female members to permit the forced passage of dental floss entirely thru and between the opposing surfaces of said male and female members when locked.

ARMAND M. OPPENHEIMER.
